DESIGN FOR A BOY'S PISTOL HOLSTER OR SIMILAR ARTICLE

Herman Iskin, Jamaica, N. Y., assignor to Sack-man Brothers Company, New York, N. Y.

Application October 8, 1934, Serial No. 53,519

Term of patent 7 years

To all whom it may concern:

Be it known that I, HERMAN ISKIN, a citizen of the United States of America, and residing in Jamaica, county of Queens, and State of New York, have invented a new, original, and ornamental Design for a Boy's Pistol Holster or Similar Article, of which the following is a specification, reference being had to the accompanying drawing, forming a part thereof.

Fig. 2 is a section on line 2—2 of Figure 1.
Fig. 3 is a section on line 3—3 of Figure 1.

I claim:

The ornamental design for a boy's pistol holster or similar article, as shown.

In testimony whereof I have signed this specification.

HERMAN ISKIN.
